UNITED STATES PATENT AND TRADEMARK OFFICE
Certificate

Patent No. D. 549,913 S

Patented: August 28, 2007

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Mark W. Bergman, Minnetonka, MN (US); Matthew V. Leyden, St. Paul, MN (US); and Jeffrey B. Waffensmith, North Oaks, MN (US).

Signed and Sealed this Second Day of July 2013.
